CLAIM

The ornamental design for a cable breakout enclosure, as shown and described.

DESCRIPTION

FIG. 1 is a perspective view of a cable breakout enclosure showing my new design;

FIG. 2 is a front view thereof;

FIG. 3 is a rear view thereof;

FIG. 4 is a side view thereof;

FIG. 5 is an opposite side view thereof;

FIG. 6 is a bottom view thereof; and,

FIG. 7 is a top view thereof.

The broken lines shown in the views are included for the purpose of illustrating portions of the cable breakout enclosure that form no part of the claimed design.
